UNITED STATES PATENT OFFICE.

HENRY SMITH, JR., OF BALTIMORE, MARYLAND.

REFRIGERATOR-BUILDING.

SPECIFICATION forming part of Letters Patent No. 224,048, dated February 3, 1880.

Application filed October 10, 1879.

To all whom it may concern:

Be it known that I, HENRY SMITH, Jr., of the city of Baltimore and State of Maryland, have invented certain Improvements in Refrigerating-Chambers, of which the following is a specification; and I do hereby declare that in the same is contained a full, clear, and exact description of my said invention, reference being had to the accompanying drawings, and to the letters of reference marked thereon.

This invention has reference to improvements in the apparatus employed, in connection with a body of ice situated at the upper part of the building wherein the refrigerating chambers or rooms are located, to effect a cool and dry atmosphere in the said chambers or rooms, and one that can be rapidly changed in temperature, as may be desired by the attendant, as will hereinafter fully appear.

In the further description of my invention which follows reference is made to the accompanying drawings, forming a part hereof, and in which—

Figure I is a sectional elevation of a building containing two of my improved refrigerating-chambers, and Fig. II a sectional plan of the same on the dotted line *x y*.

Similar letters of reference indicate similar parts in both views, and arrows denote the direction of the various currents of air in the pipes forming a part of the apparatus.

A and B are the refrigerating-chambers, located in a building directly below a body of ice which rests upon a slatted floor, C. A drip-pan, D, serves to collect the water resulting from the melting of the ice, and an overflow-pipe, *a*, conducts it, when it shall rise to a certain height in the said pan, to any convenient place either exteriorly or interiorly of the building. A second pipe, *b*, is used when the entire body of water in the pan *D* requires to be drawn off.

E is a stack designed to enforce the circulation of air in the refrigerating-chambers, as hereinafter described. The lower end of the stack is in communication with the outer air by means of the lateral opening *c*, and the upper end of the stack is provided with a suitable cap to assist in establishing the regular current in the same.

The pipe which is employed to conduct cold

air to the refrigerating-chamber is represented by F, and it commences in the stack at a point preferably below the slatted floor of the ice-chamber, and, after extending to about the top 55 of the ice-chamber and into the same, passes to below the slatted floor and branches to the refrigerating-chambers. The draft in the stack E is controlled by means of a damper, *d*, and the inlet end of the cold-air pipe F is provided with a similar device, *e*, which is operated from any convenient part of the building.

The building is further provided with ventilating stacks or shafts, with which the refrigerating-chambers are in communication, 65 and the openings for this purpose are represented by *f*, and the registers by means of which they may be closed by *g*.

Supposing the ice-chambers to be stocked with ice and the temperature of the air exteriorly of the building too high for the preservation of meats, &c., the dampers *d* and *e* and the registers *g* are opened, when the air in the vertical portion of the cold-air pipe within the ice-chamber falls, owing to its superior weight, 70 and is conducted to the refrigerating-chambers. The movement of the air in the cold-air pipe is accelerated by the draft in the stack E and the dripping of cold water from the ice upon it and its branches, and further by passing through a cold atmosphere which must necessarily be established below the slatted floor C.

The cold air, upon entering the refrigerating-chamber, falls to the floor of the same and displaces the warmer body of air, which escapes 85 by means of the openings *f*. This circulation of air in the refrigerating-chambers continues until the temperature of the same is about equal to that in the vertical portion of the cold-air pipe within the ice-chamber, or until the 90 damper *d* is closed, when it ceases. Any temperature higher than the extreme one effected, as described, and below that of the exterior air, may be obtained by regulating the various dampers and registers before alluded to. The 95 building is provided with doors for the introduction of ice, and others to admit of access to the different parts thereof, and the various chambers are lined with non-heat-conducting materials to lessen the drain upon the ice.

By means of this apparatus it will be understood that the cooling-air admitted to the re-

frigerating-chambers is taken from the exterior of the building, the air in the ice-chamber, which may be laden with impurities, being isolated therefrom. The drain on the ice is also much less, as only sufficient ice is melted to give the required temperature to the refrigerating-chambers.

I am aware that it is not new to place a coil of pipe in the ice-chamber of a refrigerator, upon which coil the ice rests, and through which air passes to be cooled on its way to the provision-chamber. I am further aware that in refrigerators an air-chamber has been constructed beneath the ice-box, for cooling the air which enters the provision-chamber situated immediately below, and that the air, upon entering the refrigerator, passes along a pipe arranged for that purpose into the cooling-chamber, where it is cooled, and by reason of its superior specific gravity falls to the bottom of the provision-chamber through a channel

provided at its rear for that purpose; and such constructions, therefore, I do not claim; but,

Having described my invention, what I claim as new, and wish to secure by Letters 25 Patent of the United States, is—

As an improvement in refrigerating apparatuses, the following elements in combination, viz: the refrigerating-chambers A and B, located below the slatted ice-floor C, drip-pan 30 D, stack E, cold-air pipe F, and suitable means for carrying off the warm air from the said refrigerating-chambers, substantially as herein described.

In testimony whereof I have hereunto subscribed my name this 8th day of April, A. D. 1879.

HENRY SMITH, JR.
